SAFETY RAZOR

Earl E. Taylor, Lynn, Mass., assignor to
Fannie E. Taylor, Lynn, Mass.

Application July 24, 1931, Serial No. 552,829

8 Claims. (Cl. 30—85)

This invention relates to safety razors and has for an object to produce a simple and efficient razor which can be made and sold at such a low price that if desired it may have a blade permanently associated therewith, the whole being thrown away after a single use or as soon as the blade has become dull.

A further object is to so form the razor that it may be dispensed readily from a coin operated dispensing machine and may have associated therewith in a single package a tube of shaving emollient.

A still further object is to so form the razor that the blades may if desired be detachably associated therewith so that all but the blade may be used repeatedly over an extended period. A still further object is to so form the razor that it may be readily manipulated for the presentation of the cutting edge or edges in the most advantageous positions, and particularly in locations difficult or impossible to properly reach with razors as heretofore made.

Further objects and advantageous constructions will appear from a more complete description of certain embodiments of this invention shown in the accompanying drawings in which

Figure 1 is a perspective of a package consisting of a razor and a tube of shaving emollient which may be dispensed as a unit.

Figure 2 is a side elevation partly broken away and in section and to a larger scale than Figure 1 of the razor itself.

Figure 3 is a section on line 3—3 of Figure 2.

Figure 4 is a fragmentary longitudinal section through a form of razor having a detachable blade.

Figure 5 is a cross section through a razor of the type shown in Figure 4 and on the section line 5—5 of Figure 4.

Figure 6 is a top plan of the same.

Figure 7 is a fragmentary perspective showing another form of blade clamping element.

Figure 8 is a fragmentary perspective of the handle and guard element for use with the clamping element shown in Figures 7 and 9.

Figure 9 is a fragmentary perspective of a retaining element cooperating with the clamping element shown in Figure 7.

Figure 10 is a section similar to Figure 4, but showing the parts illustrated in Figures 7, 8 and 9.

Figure 11 is a perspective of another form of blade clamping member.

Figure 12 is a perspective of one form of blade which may be used in connection with various forms of this invention.

Figure 13 is a perspective of the guard and handle member for cooperation with the clamping member of Figure 11.

Figures 14 and 15 are sections through the razor employing the parts shown in Figures 11 and 13 and taken on the section line 14—14 of Figure 13, the razor being opened and closed respectively.

Figure 16 is an end elevation showing the razor closed as in Figure 15.

The razor comprises a handle and a guard or support for a razor blade which consists of a plate member 1 having a portion intermediate its ends as at 2 curved to form a blade support. At each side of the curved portion 2 the plate ends 15 are bent sharply toward each other at the concave face of the portions 2 as at 3 to form inwardly curving portions 4, the ends of which are then turned outwardly away from each other as at 5 sufficiently close to the guard to present 20 their substantially parallel end edges convenient for engagement by the fingers of the user. To this end they should not be spaced from the guard by a distance substantially greater than the width of the guard and as shown they are 25 spaced slightly less than this distance. These handle edges are also substantially parallel to the cutting edge or edges of the razor blade. By manipulation between the fingers the razor may be presented at any desired angular position with- 30 in a wide range without changing the angular position of the hand, the inwardly concaved portions 4 forming depressions affording space to receive the ends of the fingers, particularly in the extreme rocked positions of the razor. 35 Preferably the edges of these end portions have recesses or indentations 6 therein which form finger holds to facilitate grasping the razor. The bent portions 3 are preferably slotted laterally at intervals to permit the passage of lather and 40 hair portions.

As shown in Figures 1, 2 and 3 the razor blade at 9 may be permanently secured against the convex outer face of the portion 2. To this end a clamping element 7 is placed over the outer face 45 of the blade and the blade clamping element and guard portion 2 are permanently secured together as by the tubular rivets 8 which are passed through the end holes of the blade, double edge blades as made commercially being provided 50 with such holes. This form of the razor where the blade is permanently fixed is particularly suitable for dispensing from a coin operated dispensing machine and such machines may be conveniently provided in wash rooms of railroad cars, 55

hotels, or the like, so as to be convenient for a traveler who may wish to use the razor a single time and then discard it, or if desired he may use it as long as the blade remains in good condition. When the razor is to be dispensed in this manner the formation of the handle adapts it admirably to have packaged with the razor a suitable receptacle such as a collapsible tube indicated at 10 in Figure 1 which may contain a shaving emollient. This may be held frictionally between the portions 4 of the razor and may be removed by the purchaser for use as desired. This tube, as shown in Figure 1, may be provided with the usual screw cap 11 which may be removed by the user and the contents of the tube may then be squeezed out by collapsing the tube.

The razor may be made up in forms which permit the detachment of a razor blade for the insertion of a new blade when desired and certain constructions to this end are shown in Figures 4 to 10. Referring first to Figures 4, 5 and 6, the razor supporting portion 20, instead of being provided with holes for the reception of rivets is provided with inwardly offset tongues 21 with which may cooperate similarly inclined tongues 22 of the clamping member 23 which may be projected through the holes 24 of the razor blade and engaged beneath the tongues 21. The clamping member 23 is shaped in general similarly to the clamping element 7 shown in Figures 1 and 3. By moving the handle member and clamping element relatively laterally of the direction of curvature of the blade supporting portion 20 the blade may be clamped or released from its position. The portions 21 and 22 which form cooperating wedge elements are shown as arranged to an angle of about 14° and 30' from the transverse axis of the portion 20, this being found in actual practice to prevent accidental detachment of the parts and yet permit them to be moved readily to clamp or release the blade whenever desired, and by forming the roots of the portion 22 oppositely curved with their concavities facing each other as shown in Figure 6, they will properly cooperate with either round holes or straight edge faces of the blade 6 holding them against lateral motion. If desired, one or both portions 22 may have a projection 25 formed to snap into a hole 26 in the portion 21 when the blade is in changed position to prevent accidental disengagement of the parts. The clamping member may, if desired, be provided with a central depression 27 which stiffens it and facilitates moving the member with the fingers. The blades are formed initially flat and the bending thereof produced by the relative sliding of the handle member and clamping element holds these parts under frictional engagement and prevents the parts from too ready detachment while permitting sufficient bending of the blade to bring it down tight against the convex face of the portion 20 when desired. The amount of relative motion furnishes a means for adjusting the curvature of the blade and thus the closeness of the shave.

In Figures 7 to 10 a still further modification is shown in which the handle member is formed with spaced holes 30 corresponding to the spacing of the holes in the blade and the clamping element 31 is provided with posts 32 which may be passed through the blade holes and the holes 30 of the handle member. These posts 32 are formed with heads 34 provided with inclined upper faces 35 with which cooperate inclined wing elements 36 of a clamp retaining element 37. This element 37 has a slot 38 therethrough terminating in a

hole 39 through which each of the posts 32 may be passed and then by an axial movement of the member 37 the wings 36 may be drawn into engagement with the faces 35 of the element 31 drawn down against the blade to clamp it against the convex face of the blade supporting portion of the handle. The member 37 may be provided with a down turned handle portion 40 by which it may be grasped. By an inspection of Figures 3 and 5, it may be seen that a cross section 10 through the razor transverse to the cutting edges of the blade and through the handle presents an exterior outline which may be inscribed in a substantially rectangular or square figure, the out-turned end edges of the handle lying substantially in adjacent corners of the figure and the blade being substantially parallel to one side of the figure.

In Figures 11 to 16 another form of this invention is illustrated in which the combined handle 20 and guard member 50 and the blade clamping member 51, shown detached in Figures 13 and 11, respectively, are permanently secured together as by a hinge connection. To this end the clamping member 51 is provided with a pair of 25 ears 52 struck inwardly therefrom the member 50 is provided with ears 53 similarly formed. Through mating perforations in these ears is passed a pintle pin 54 and in order that the insertion or removal of blades may be facilitated 30 these members 50 and 51 are yieldingly held apart as shown in Figure 14 as by means of a coil spring 55 surrounding the pintle 54 and having one end hooked about one of the ears 52 of the blade clamping member and the other engaged 35 back of a lug 56 struck inwardly from a handle portion 57 of the member 50.

The member 50 is also provided with a pair of upwardly struck lugs 58 spaced to engage in the opening portions 59 of a blade 60 as shown in Figure 12. This blade, as shown, is provided with a slot 61 connecting the opening 59 with a central perforation 62 but a blade provided with three longitudinally spaced holes may be employed in this form of razor equally well, the lugs 58 engaging through the end holes of such a blade. The blade being placed in position over the lugs 58, which hold the blade properly centered, the free end of the clamping plate 51 is brought down against the blade into the position shown in Figure 15, and a screw 65 rotatable in a sleeve 66 and carried rigidly by the member 50 as its threaded end portion 67 engages in a mating threaded socket 68 in the member 51 so that by turning the screw 65 the member 51 may be 65 brought down firmly into clamping relation with the blade to hold it against the outer face of the member 50.

In order that the screw 65 may not become detached from the member 50, it is shown as provided with a portion 68 of reduced diameter within which is engaged the inner end of a set screw 69 threaded through the sleeve 66. This permits the screw 65 to have a limited lost motion axial movement sufficient to permit its upper end 67 to be retracted to a point where it does not interfere with the placing or removal of the blades and which permits the member 51 to be closed down tight against the blade before the threaded end 67 engages in the socket 68. When 70 the parts have been brought into cooperative position the screw is turned, as by manipulation of its knurled head 70, to cause the end 67 to enter the socket and pull the member 51 down tight to clamp the blade firmly between this 75

member and the member 50, the thrust of the screw being taken between the upper face of the head 70 and the end of the sleeve 66, as shown in Figure 15.

5 From the foregoing description of certain embodiments of this invention, it should be evident to those skilled in the art that various changes and modifications might be made without departing from the spirit or scope of this invention as defined by the appended claims.

10 I claim:

15 1. A razor having a blade provided with a straight cutting edge, a guard for said blade, and a handle portion presenting a pair of spaced substantially parallel edges substantially parallel to said blade cutting edge for engagement by the fingers of the user, said pair of edges being spaced from said guard a distance not substantially greater than the width of said guard, said handle portion having depressions between said 20 pairs of edges and said guard to receive the ends of the fingers engaging said pair of edges.

25 2. A razor having a handle, and a blade having a cutting edge, said razor presenting in cross section through said handle and transverse to said cutting edge an exterior outline which may be inscribed in a substantially rectangular figure, said handle having edges for engagement by the fingers of the user and lying in said outline substantially in adjacent corners of said figure.

30 3. A razor having a handle, and a blade having a cutting edge, said razor presenting in cross section through said handle and transverse to said cutting edge an exterior outline which may be inscribed in a substantially square figure, said handle having edges for engagement by the fingers of the user and lying in said outline substantially in adjacent corners of said figure.

35 4. A combined safety razor blade support and handle, which comprises a single strip of sheet material having a portion intermediate its ends formed as a blade support, said end portions being turned inwardly toward each other along opposite sides of said support and terminating turned outwardly away from each other to form a handle presenting end edges to the fingers.

5 5. A combined safety razor blade support and handle, which comprises a strip of sheet material having a portion intermediate its ends formed as a blade support, said end portions being turned inwardly toward each other along opposite sides of said support and terminating turned outwardly away from each other to form a handle, the end edges of said strip having indentations forming finger holds.

10 6. A razor comprising a plate member having a blade supporting portion provided with a pair of openings therethrough, a blade having a pair of openings therethrough for registry with said plate openings, and a blade retaining element having a pair of tongues struck therefrom and both facing in one direction and positioned to be passed through said blade and plate member openings and engaged with the back face of said plate member on movement of said element in one direction substantially in line with said 20 tongues, the roots of said tongues being curved in opposite directions with their concavities facing to cooperate with either round holes or straight edge faces of the blade openings.

25 7. A razor comprising a plate member having a blade-supporting portion and portions projecting on one side from opposite edges of said supporting portion, and together forming a handle for the razor, a clamp hinged to said member at one end of said blade-supporting portion, a sleeve 30 carried by said plate member between said projecting portions, and means carried by said sleeve for securing said clamp in position to clamp a blade to said supporting portion.

35 8. A razor comprising a plate member having a blade-supporting portion and portions projecting on one side from opposite edges of said supporting portion and having outwardly turned ends together forming finger-engaging portions of a handle for the razor, a clamp hinged to said 40 member at one end of said blade-supporting portion, and means extending between said projecting portions for securing said clamp in position to clamp a blade to said supporting portion.

45 EARL E. TAYLOR.
